UNITED STATES PATENT OFFICE.

DUNCAN McLEAN, OF NORTH SHIELDS, ENGLAND.

DESIGN FOR A POT OR COWL FOR CHIMNEYS OR VENTILATING-SHAFTS.

No. 39,871.

Specification for Design.

Patented March 9, 1909.

Application filed March 2, 1908. Serial No. 418,895. Term of patent 14 years.

To all whom it may concern:

Be it known that I, DUNCAN McLEAN, a subject of the King of Great Britain and Ireland, residing at 11 Windsor Gardens, North Shields, in the county of Northumberland, England, have invented a new, original, and ornamental Design for a Pot or Cowl for Chimneys or Ventilating-Shafts, of which the following is a specification, reference being had to the accompanying drawing, forming part thereof.

The figure is an elevation of a pot or cowl showing my new design.

The design comprises the following distinguishing and salient features, viz:—a hood *a* depending over the end of the pipe or shaft *b* and having a frusto-conical upper

portion *c*; flat rings or annular disks *d* of decreasing size arranged cone-fashion above the hood *a* and supported therefrom by three inclined supports *e*, the lowermost and largest ring or disk being of less diameter than the hood *a*; and a conical terminal or cap *f* surmounting the uppermost ring or disk.

I claim:

The ornamental design for a pot or cowl for chimneys or ventilating shafts as shown and described.

DUNCAN McLEAN.
